(57) **CLAIM**

The ornamental design for a controller for electronic device, as shown and described.

DESCRIPTION

FIG. 1 is a perspective view of a controller for electronic device, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is another perspective view thereof, as shown in another configuration; and,

FIG. 9 is still another perspective view thereof, as shown in a further configuration.

The broken in the figures show portions of the controller for electronic device which form no part of the claimed design.

FIG. 8 discloses the invention of FIGS. 1-7 as separated in two parts while FIG. 9 discloses the same invention as joined together.
